Atty's.

UNITED STATES PATENT OFFICE.

GEORGE W. KINGSLEY, OF BUFFALO, NEW YORK.

DESIGN FOR PICTURE-FRAME CORD OR WIRE.

Specification forming part of Design No. 7,483, dated June 9, 1874; application filed March 3, 1874.
[Term of Patent 7 years]

To all whom it may concern:

Be it known that I, GEORGE W. KINGSLEY, of Buffalo, Erie county, New York, have invented a new and original Design for a Cord for Picture-Frames, of which the following is a specification:

This design is fully illustrated in the accompanying drawing, where it is shown as applied to a picture-frame, A; and it consists of a cord or wire, on which is formed or attached a series of leaves or flowers, giving the cord

the appearance of a vine, as shown in the accompanying drawing.

I claim—

The design for a cord for picture-frames, substantially as herein shown and described.

In witness whereof I have hereunto signed my name in the presence of two subscribing witnesses.

Witnesses: G. W. KINGSLEY.

J. R. DRAKE,
T. H. PARSONS.
